(57) **CLAIM**

The ornamental design for an ice jacket wine chiller, as shown and described.

DESCRIPTION

FIG. 1 is a top front perspective view of an ice jacket wine chiller showing my new design, with all the pods in an assembled configuration;

FIG. 2 is a top front perspective view thereof, showing the ice jacket wine chiller in a slightly rotated configuration;

FIG. 3 is a top front perspective view showing the ice jacket wine chiller with just one pod assembled for ease of illustration;

FIG. 4 is a front elevation view of FIG. 1;

FIG. 5 is a top plan view thereof;

FIG. 6 is a cross sectional view thereof, taken along line 6-6 in FIG. 5; and,

FIG. 7 is an enlarged view of the circled area labeled "7" in FIG. 6.
